UNITED STATES PATENT OFFICE.

FRANK WEBB, OF TORRANCE, CALIFORNIA.

AUTOMATIC GAS CUT-OFF DEVICE.

Application filed January 26, 1925. Serial No. 4,931.

My invention relates to automatic cut-off devices for gas mains, and the purpose of my invention is the provision of an automatically operated cut-off device having the desirable qualities of simplicity, cheapness, and durability, and which operates upon any reduction in pressure of gas or other fluid in a main to discontinue the flow of gas to or through branch or feed pipes, thus preventing subsequent leakage through unlighted burners and danger of asphyxiations or explosions.

It is also a purpose of my invention to provide an automatic gas cut-off device of the above described character embodying a valve carrying member normally urged to a position in which the valve is closed but responsive to a predetermined pressure of gas to maintain a position in which the valve is open, and a manually operable element for moving the member to the last mentioned position.

I will describe only one form of automatic gas cut-off device embodying my invention and will then point out the novel features thereof in claims.

In the accompanying drawings,

Figure 1 is a view showing in vertical longitudinal section one form of automatic gas cut-off device embodying my invention in applied position within a gas supply pipe.

Figure 2 is a fragmentary vertical sectional view of the device with the movable parts thereof in the other extreme position from that shown in Figure 1.

Figure 3 is a vertical transverse sectional view taken on the line 3-3 of Figure 1.

Referring specifically to the drawings in which similar reference characters refer to similar parts in each of the views, my invention in its present embodiment comprises a body B of metal or other suitable material constructed to provide interiorly thereof a chamber 15, and an inlet passage or duct 16 having its inlet end exposed at one end of the body and constructed to provide a conical socket 17. The outlet end of the passage 16 communicates with the top of the chamber 15. The body B is also formed with an outlet passage 18, the inlet end of which communicates with the top of the chamber 15 and is constructed to provide a conical socket 19. The outlet end of the passage 18 communicates with a chamber 20 in a tubular extension 21 exteriorly threaded to per-

mit connection with one section 22 of a gas supply pipe. On the other end of the body B is formed an exteriorly threaded collar 23 which is engaged by the threaded end of a pipe section 24, the latter in turn being 60 threadedly connected to another section 25 of the gas supply pipe.

The body B, is formed with a slot 26 and extending through the slot is a member 27 in the form of an elongated plate which is mounted for rocking movement by means of a pin 28. The walls of the slot 26 are inclined as shown to permit the member 27 to occupy the inclined position shown in Figure 1, the lower portion of the member being 70 disposed within the chamber 15 and contacting with an inclined surface 29 which constitutes a continuation of the lower wall of the slot 26. This lower end of the member 27 is formed with a conical valve 30 adapted to 75 snugly fit within the socket 19 to close the entrance end of the passage 18. A port 31 is formed in the member 27 which is normally closed as shown in Figure 1 but which is opened and in registration with the outlet 80 end of the passage 16 when the member 27 is in the position shown in Figure 2. The upper end of the member 27 is formed with a conical head 32 adapted to set within the socket 17 when the member is in the position 85 shown in Figure 1. A port 33 is formed in the member 27 so as to extend through the head 32 and thus provide communication between the pipe section 24 and the passage 16 when the member 27 is in the position shown 90 in Figure 1.

For the purpose of moving the member 27 from the position shown in Figure 2 to that shown in Figure 1, I provide a manually operable element 34 which is in the 95 form of a ring rotatable in the pipe section 24 by trunnions 35, one of which is provided with a handle 36 which is adapted to be gripped in rotating the ring.

In practice, the normal pressure of gas 100 flowing through the supply pipe maintains the member 27 in the extreme position shown in Figure 1 wherein the head 32 is within the socket 17, the port 31 closed, and the valve 30 in open position wherefore it will 105 be seen that gas is free to flow through the port 33, inlet passage 16, chamber 15, outlet passage 18, and into the chamber 20. As long as the pressure of gas remains normal, the member 27 will occupy this extreme po- 110

sition, but as soon as there is any appreciable reduction in pressure, the member 27 will gravitate to the other extreme position shown in Figure 2. The movement of the member to this position is a result of the fact that that portion of the member above the pivot 28 is heavier than the portion below the pivot. In this extreme position of the member 27 the valve 30 is seated within the socket 19 so as to close the inlet end of the passage 18 and thus prevent the further flow of gas to the chamber 20. In this position of the member 27, the port 31 is in registration with the outlet end of the passage 16 permitting gas to flow into the chamber 15 and thus prevent the gas acting on the member to return the latter to the other extreme position.

When desiring to restore the flow of gas through the device, the member 27 can be returned to the extreme position shown in Figure 1 by rotation of the element 34 in the direction indicated by the arrow in Figure 2 thus moving the valve 30 to open position and positioning the member so that the pressure of gas will act to retain the member in this position against its tendency to gravitate to the other extreme position.

Although I have herein shown and described only one form of automatic gas cut-off device embodying my invention, it is to be understood that various changes and modifications may be made therein without departing from the spirit of the invention and the spirit and scope of the appended claims.

I claim as my invention:

1. An automatic gas cut-off device comprising a body having a valve chamber therein, an inlet passage communicating with the chamber, and an outlet passage communicating with the chamber, a member supported for movement in the body to occupy two extreme positions and normally urged to one extreme position, a valve adapted to close the outlet passage when the member is in non-urged position, a port in the member through which gas can flow to the inlet passage when the member is in the non-urged position whereby the pressure of the gas is caused to maintain the member in the non-urged position, a head formed on the member, the entrance ends of the passages formed with conical sockets, and the head and valve being of conical form to fit respectively in said sockets.

2. An automatic cut-off device comprising a body having a valve chamber therein, an inlet passage communicating with the chamber and an outlet passage communicating with the chamber, a member supported for movement in the body to occupy two extreme positions and normally urged to one extreme position, a valve adapted to close the outlet passage when the member is in non-urged

position, a port in the member through which gas can flow to the inlet passage when the member is in the non-urged position whereby the pressure of the gas is caused to maintain the member in the non-urged position, an element manually rotatable to move the member from the urged position to the non-urged position whereby an opening of said valve is effected. 70

3. An automatic gas cut-off device comprising a body having a valve chamber therein, an inlet passage communicating with the chamber and an outlet passage communicating with the chamber, a member supported for movement in the body to occupy two extreme positions and normally urged to one extreme position, a valve adapted to close the outlet passage when the member is in non-urged position, a port in the member through which gas can flow to the inlet passage when the member is in the non-urged position whereby the pressure of the gas is caused to maintain the member in the non-urged position, a ring mounted for rotation to engage the member and move the latter from the urged position to the non-urged position to effect an opening of said valve. 80

4. An automatic gas cut-off device comprising a body having a valve chamber therein, an inlet passage communicating with the chamber and an outlet passage communicating with the chamber, a member supported for movement in the body to occupy two extreme positions and normally urged to one extreme position, a valve adapted to close the outlet passage when the member is in non-urged position, a port in the member through which gas can flow to the inlet passage when the member is in the non-urged position whereby the pressure of the gas is caused to maintain the member in the non-urged position, a pipe section connected to the body, and a ring rotatably mounted in the pipe section to engage the member for moving the latter from the urged position to the non-urged position to effect an opening of said valve. 90

5. An automatic gas cut-off device comprising a body having a valve chamber therein, an inlet passage communicating with the chamber and an outlet passage communicating with the chamber, a member supported for movement in the body to occupy two extreme positions and normally urged to one extreme position, a valve adapted to close the outlet passage when the member is in non-urged position, a port in the member through which gas can flow to the inlet passage when the member is in the non-urged position whereby the pressure of the gas is caused to maintain the member in the non-urged position, a valve for closing the port and means for supporting the valve so as to maintain the latter in open position by 100

the predetermined gas pressure and to automatically close the valve when the gas pressure is reduced from the predetermined pressure.

- 5 6. An automatic gas cut-off device comprising a body having a valve chamber therein, an inlet passage communicating with the chamber and an outlet passage communicating with the chamber, a member supported for movement in the body to occupy two extreme positions and normally urged to one extreme position, a valve adapted to close the outlet passage when the member is

in non-urged position, a port in the member through which gas can flow to the inlet 15 passage when the member is in the non-urged position whereby the pressure of the gas is caused to maintain the member in the non-urged position, a valve for closing the port and means for supporting the valve so 20 as to maintain the latter in open position by the predetermined gas pressure and to automatically close the valve when the gas pressure is reduced from the predetermined pressure.
